UNITED STATES PATENT OFFICE

LYMAN STEWART, OF TITUSVILLE, PENNSYLVANIA.

IMPROVEMENT IN PACKERS FOR OIL-WELLS.

Specification forming part of Letters Patent No. 171,589, dated December 28, 1875; application filed December 1, 1875.

To all whom it may concern:

Be it known that I, LYMAN STEWART, of Titusville, in the county of Crawford and State of Pennsylvania, have invented certain new and useful Improvements in Packer for Oil-Wells; and I do hereby declare that the following is a full, clear, and exact description thereof, which will enable others skilled in the art to which it appertains to make and use the same, reference being had to the accompanying drawings, and to the letters of reference marked thereon, which form a part of this specification.

Figure 1 represents my packer with the fibrous portion in the position or shape which it ordinarily assumes when such fibrous portion is free from unusual or imposed tension or compression. Fig. 2 is a vertical section of the same, and Fig. 3 represents it under compression.

The object of my invention is to provide a packing for the tubes of oil or other artesian wells, which may be readily introduced or withdrawn through a casing or hole that is much smaller than the space that it is desired to pack, and which shall also be certain in its operation, safe to use under all ordinary circumstances, and possess the additional advantage of being both cheap and durable.

In the drawings, A represents the tube, to be packed with the ordinary couplings or thimbles A¹ A². Under certain circumstances this tube may be perforated, as at a², for a purpose which will be explained. B represents the upper end of an anchor, which stands upon the bottom of the well, and extends up to a point in the well where it is desired to locate the packer. The inside diameter of this anchor should be enough greater than the outside diameter of the tube A to admit the coupling or thimble A². The upper end of the anchor is reduced by any suitable means so as to closely fit the tube A. For conveniently securing the lower end of the packing C, I usually prefer to elongate this reduced part to, say, two or three inches, and on the upper end of the reduced part have a small rib or flange turned, as shown at b¹, Fig. 2, the lower end of the reducer forming an inner rib or shoulder, b, Fig. 2, against which the coup-

ling or thimble A² strikes when the tubing is being lowered into or withdrawn from the well, thus supporting the weight of the anchor. For the purpose of filling the space between the tube A and the walls of the well, so as to prevent the water above from descending into the oil-rock, or to prevent the gas escaping from the oil, I use a fibrous packing, C, (consisting of common hemp-packing, cotton-wicking, or any other suitable fibrous material,) woven or braided around the tube A, substantially as shown in Fig. 1—that is, with the middle portion woven or braided more loosely than the ends. The packing may be secured, the lower end in the groove or recess formed by the flange or rib turned on the top of the reducer, on the upper end of the anchor B, as shown at b¹, Fig. 2, (preferably by winding very tightly with cord or wire c,) or it may be secured below the collar on the upper end of the same, the other end being secured to the tube A by being tied above an ordinary coupling, or a band, or ring placed at the proper point for the purpose. By preference I produce the desired increase in the size or swell of the part C, Fig. 3, by braiding or weaving the central portion more loosely than the ends, as indicated in the drawings; but when desired this shape may be made by using more material in the center, or by any other suitable means.

For a packer to be used on the ordinary pumping-tube through five and five-eighths inch casing, (the usual size,) I take a tube of from four to five feet in length, or thereabout, and use from three to four pounds of packing, according to circumstances; and for a packer to be used through three and one-fourth inch casing, (the usual small size,) I use a tube of about one inch inside diameter and about six feet in length. The tube A should first be dressed off smoothly, so as to slide freely through the packing when it is being compressed.

Before inserting the packer in the well, the packing should be saturated with a preparation of tallow and bees-wax or other suitable preparation, not only to make the mass when compressed more dense and impervious to water or gas, but to make the strands of the

packing material draw and render over and around each other more freely when the weight of the tubing above comes upon them.

When the tubing having my packer applied thereto is let down into the well, the weight of the anchor B will insure that the fibrous section C will be kept stretched out, as in Fig. 1, until the lower end of said anchor touches the bottom of the well, when the weight of the tubing above will compress the part C into substantially the form shown in Fig. 3, except that the sides will be nearer straight, being compressed against the sides of the well.

I usually prefer that the increase or swell in the central part of C, Fig. 3, shall be produced by weaving, braiding, or otherwise making that portion of looser texture than the ends of this section, in order that when compressed the ends being the firmest shall yield less to the weight of the superincumbent tubing, and shall not, therefore, be "telescopied" over and upon the tubing A or the anchor B. This feature is important, as such doubling back upon either the tube A or the anchor B may defeat the very object for which the packer is used by causing it to leak, and, besides, may render it difficult to withdraw the tubing from the well.

The tube A should fit closely within the rib or reduced portion b, so that the packing cannot be forced into this joint.

When the tube A is to be used as a flowing-tube, after the Stevenson method, it (the

tube) may be perforated, as at a², the anchor being correspondingly perforated, as at b², Fig. 3, in order that the mingled oil and gas may enter the flowing-tube at a point close below the packer. In ordinary cases I propose to contract the size of the anchor below the point to which the tube A is forced by the pressure from above, thus effecting in some wells a great saving in expense.

It is apparent that when tube A is lowered into or lifted from the well the thimble A² will engage with the rib or shoulder b upon the inside of the upper end of the anchor, and thus carry the anchor without allowing any injurious strain to come upon the packing C.

Having thus described my invention, what I claim is—

1. The packing C, of a close firm texture at the ends, and loose in texture in the center, substantially as set forth.
2. The combination of the tube A and anchor B, united by a telescopic joint with the fibrous packing C, substantially as set forth.
3. The anchor B, provided with the perforations b², in combination with the perforated tube A, substantially as set forth.

In testimony that I claim the foregoing as my own I affix my signature in presence of two witnesses.

LYMAN STEWART.
